Primary Examiner — Kelley Donnelly(74) *Attorney, Agent, or Firm* — Merchant & Gould P.C.(57) **CLAIM**

The ornamental design for a modular container, as shown and described.

DESCRIPTION

FIG. 1 is a front perspective view of a modular container showing my new design;

FIG. 2 is a rear perspective view of the modular container;

FIG. 3 is a front view of the modular container;

FIG. 4 is a rear view of the modular container;

FIG. 5 is a right side view of the modular container;

FIG. 6 is a left side view of the modular container;

FIG. 7 is a top view of the modular container; and,

FIG. 8 is a bottom view of the modular container.
